UNITED STATES PATENT OFFICE

HENRY RESCH, OF BAYONNE, NEW JERSEY, ASSIGNOR TO UNDERWOOD ELLIOTT FISHER COMPANY, OF NEW YORK, N. Y., A CORPORATION OF DELAWARE

TYPEWRITING MACHINE

Application filed December 19, 1927. Serial No. 240,991.

This invention relates to typewriting machines wherein an auxiliary inking ribbon is interposed between superposed work-sheets for manifolding, especially of bills or statement-sheets and a record-sheet. The invention is shown in connection with an auxiliary ribbon-device, such as disclosed in co-pending application of Jesse A. B. Smith, Serial No. 177,884, filed March 24, 1927, (now Patent No. 1,764,900, dated June 17, 1930), and deals largely with means for guiding the leading end of work-sheets up past the printing line, the object being to minimize time and labor during their insertion around the platen from the rear thereof.

The auxiliary ribbon is fed from a spool at one side of the platen-carriage down to the printing line, then in a horizontal stretch along the printing line to be led up again and wound upon a corresponding spool opposite the first one. The horizontal or active stretch of the ribbon is held upon the printing line close to the platen by a displaceable ribbon-carrier, which allows said active stretch to be swung upwardly and forwardly clear of the platen when the record-sheet is to be inserted from the rear.

Difficulties have been experienced when inserting a record-sheet with the auxiliary ribbon in raised inoperative position, in that the leading edge of the paper, normally flaring away from the platen-surface at the front thereof, would clash with the auxiliary ribbon or parts of the ribbon-holder, causing the operator to use her fingers in guiding the leading paper-edge rearwardly to prevent its getting wrinkled or injured.

According to this invention a displaceable paper-guide is provided, which, normally out of function, may be rendered active to guide or deflect the paper across the typing line closely to the platen-surface and clear of the obstructing parts, when the auxiliary ribbon is swung to inoperative position.

Preferably the displaceable ribbon-holder and the displaceable paper-guide are cooperative and timed to each other in such a way that the movement which displaces the active part of the auxiliary ribbon automatically causes the paper-guide to deflect the

paper, relieving the operator's mind and keeping her fingers from getting smudged against the displaced auxiliary inking ribbon, while in turn protecting the paper from getting soiled.

The present embodiment includes a lever having a swinging movement in a horizontal plane and fulcrumed upon the front bar of an Underwood platen-frame. One end of the lever is formed to co-operate with a cam-member, which forms part of one side of the movable ribbon-carrier, while the other end of the lever is formed with a paper-deflecting blade in cross-section conforming to the platen-surface. As the auxiliary ribbon is being displaced to inoperative position, said cam-member will bring the blade-like paper-deflecting part of the lever against suitable spring-pressure into proximity with the platen-surface.

After the record-sheet is positioned, the inking ribbon is restored for typing while the paper-guide recedes, and a small bill or statement sheet is usually front-inserted over the ribbon and record-sheet.

It is understood that a movable front paper-guide substantially as herein proposed may also be used with advantage as a mechanism in itself or in connection with other attachments or devices and wherever a certain guidance of the leading paper edge over and beyond the typing line is desired for convenience during insertion.

Other features and advantages will hereinafter appear.

In the accompanying drawings,

Figure 1 is a perspective view, showing the auxiliary ribbon-mechanism upon an Underwood platen-frame in working position, with the associated novel paper-guide spring-held in inactive position.

Figure 2 is a cross-sectional elevation of Figure 1, with the auxiliary ribbon operative and the front paper-guide out of function.

Figure 3 is a similar view, showing the auxiliary ribbon inoperative, and the front paper-guide effective for guiding the record-sheet during insertion from the rear.

Figure 4 is a part-sectional plan view diagrammatically showing the novel paper-

guide in operative and (dot and dash) inoperative positions.

A platen 10 is revolubly mounted in a platen-frame, which includes sides 11 to carry 5 journaled therein a platen-shaft 12 rotatable by a finger-wheel 12^a. A paper guide or deflector 13 may rigidly connect the sides 11, said paper-guide extending back and around the lower part of the platen, and a front rail 10 14 of the well-known Underwood platen-frame may support a novel front paper guide or deflector 14^a, as hereinafter described. Figure 1 of the drawings shows an auxiliary inking ribbon 15 for duplicating purposes, 15 operative upon the platen between a record-sheet 16 and a statement-sheet 17, the latter being written upon by means of a usual type-bar 18 and the usual oscillating ribbon 19 (fractionally indicated in dot and dash).

20 The mechanism which handles the auxiliary ribbon is in the form of an attachment mounted upon the ordinary Underwood platen-frame and herein shown to include brackets 19^a mounted upon the flanges 20 which 25 form the top of the sides 11. Said brackets 19^a, in effect forming continuations of the sides of the platen-frame, may be rigidly interconnected by an integral cross-bar 21. Said bar carries, at either end, and mounted 30 upon the back face thereof, a rising bracket 22, upon which is mounted a spool 23 by means of a stud or axle 23^a to handle the auxiliary ribbon 15, which is carried from one spool downwardly to the typing line, then along 35 the typing line to present a horizontal or typing stretch to the type-bar, to be led upwardly again for delivery upon the other spool. A mechanism to feed the ribbon is not shown on the drawing although indicated 40 by a ratchet-wheel 24 shown on the left-hand spool.

A ribbon-deflector or angle guide 25, over which the ribbon folds, adjacent either end of the platen, determines the horizontal 45 stretch of the auxiliary ribbon, said deflectors forming part of a swingable ribbon-carrier, which serves to displace the horizontal part of the ribbon to allow the advancing front edge of the record-sheet to cross the typing 50 line when being inserted from the rear. To constitute the swingable ribbon-carrier, the deflectors 25 form the terminals of a flat bar 26, which, in addition, has forward angular extensions 27, which confine the ribbon-carrier 55 between brackets 28 mounted upon the front face of the above-mentioned connecting cross-bar 21. These extensions are formed at the ends with vertical arms 29 (see Figure 1), both of which have double pin-and-slot connection with their adjacent brackets 28, the slots being shaped in such manner as to 60 guide the ribbon-carrier in a suitable shifting or cradling movement. To shift the ribbon-carrier in its slots, a rock-shaft 29^a is journaled in the brackets 19^a and operable

by a lever 30 formed with a finger-piece 31. Forwardly-extending crank-arms 32 are secured to the rock-shaft 29^a to align with the outer side face of each bracket 28, with the free ends provided with studs 33 that pass through slots 34 provided in said brackets 28 concentrically to the rock-shaft 29^a, said studs 33 to pivotally support the upper ends of the pair of vertically-disposed arms 29. The lower parts of the arms 29 carry studs 34^a 70 that pass through slots 35 and are slidably held against the faces of the brackets 28 by the heads of the studs bearing against the opposite faces of the brackets 28. Slot 35 is a compound slot and formed by the merging of two arcuate slots 36, providing for an intermediate position of the ribbon-carrier (not shown on the drawing). Raising of the finger-piece 31 results in rocking the shaft 29^a to raise the arms 32 to advance the studs 33 and 34^a along their respective slots from the normal position of Figures 1 and 2 to the position shown at Figure 3. At 37 in Figures 3 and 4 are indicated paper-guiding members in the nature of the usual wing-scales disposed at either side of a usual type-guide 37^a and stationarily mounted upon the machine-frame. These members 37 are to guide the work-sheet from the deflector 13, until close to the typing line, and, in the present case, are provided with horizontal flanges 38 at the top for the further purpose of facilitating the front insertion of small work-sheets. A cam-pin 38^a is rigidly provided upon the inner face of each bracket 28 and co-operates with a cam-face 39 formed upon the vertical arms 29, so as to assist in guiding the movable ribbon-carrier when the studs 34^a thereon are sliding from intermediate to upper extreme position within the compound slots 35. A detent-sector 40 is secured upon the left-hand end of the rock-shaft 29^a and has three notches 41 to co-operate with a pawl 42 held under spring-tension 43, said notches corresponding to extreme and intermediate 90 positions of the rock-shaft 29^a.

When a record-sheet is to be inserted at the rear of the platen, to be positioned under the auxiliary inking ribbon, the latter will be displaced, as described above, from its position in Figures 1 and 2 to the Figure 3 position. A glance at Figure 3 shows that the leading edge of the paper, if not otherwise directed, is liable to flare away from the platen-surface in leaving the scales 37 and catch on the auxiliary ribbon 15 or parts of the ribbon-carrier, as on the flat bar 26 or the rock-shaft 29^a, requiring the operator's attention to manually deflect the paper to the rear, clear of the obstructing parts.

The novel deflector 14^a, designed to improve this manual paper-guiding operation, includes a lever 44 of flat material, which, intermediate its ends, has integral bent-over ears 45 to receive a fulcrum pin or screw 46, 130

supported upon a U-shaped bearing member 47 (see Figure 3), which is screwed at 48 to the front rail 49, which is of angular cross-section and is part of the platen-frame mentioned above. The lever 44, at its right-hand end, is formed with an upward angular extension 50, to present a cam-face for a cam-member 51, the latter forming a lower extension upon the right-hand vertical arm 29 of the ribbon-carrier. As the ribbon-carrier is raised, a bent-over end 52 of said extension 51 will urge said angular extension 50 of lever 44 against the pressure of a leaf-spring 53 to cause the opposite end of the lever 44, which is enlarged to form a paper guiding or deflecting blade 54, to swing towards the platen substantially to take the place of the now ineffective ribbon 15 (see Figure 3). The paper-guiding blade 54 is shaped to conform to the platen-surface, and, while having proper clearance therewith, is effective to deflect the record sheet, to clear the obstructing ribbon-mechanism, said record-sheet being inserted and fed around the platen with the aid of usual feed-rolls 55.

After the record sheet is positioned, for type manifolding, the finger-piece 31 may be depressed to lower the auxiliary ribbon to working position (see Figure 2), simultaneously causing the paper-guiding blade 54 to recede to ineffective position, as clearly seen from Figures 1 and 4. The bill or statement sheet 17 then may be front-inserted over the auxiliary ribbon 15, and collated over the record sheet upon the usual collating table and between the collating members 56, which are fast to the connecting cross-bar 21.

It will be understood that by a single operation of lifting the finger-piece 31, the ribbon is displaced from the typing line and the deflector 54 displaced to a paper-deflecting position at the platen and both deflected members locked by the detent 42 in their key-displaced positions, leaving the operator's hands free to insert a record-sheet to the feed-rollers 55, and, by a forward spinning movement of the platen, the record-sheet is quickly advanced over the typing line and under the ribbon to the first typing line thereon, the displacements being automatic to the manual operation of the finger-piece. It will be noted at Figure 2 that the spring 53 normally holds the deflector 54 against the carriage rail and that the detent 42 holds the ribbon-carrier away from actual contact with the platen and prevents actual contact between the arm 50 and the cam 51, so that the ribbon-carrier can adjust itself to various thicknesses of superposed manifold sheets; and that the working space shown between the cam and arm provides clearance for initially lifting the ribbon vertically over the typing line before motion is conveyed to the deflector to avoid possible interference between the displaceable deflector and ribbon.

Variations may be resorted to within the scope of the invention, and portions of the improvements may be used without others.

Having thus described my invention, I claim:

1. In a typewriting machine, the combination with a carriage having a platen and a ribbon-mechanism having a ribbon stretch normally operative to cover the whole typing line of the platen and manually operable means for withdrawing the ribbon from the platen to a non-typing position to facilitate the insertion of a work-sheet around the platen to the typing line of a work-sheet deflector mounted upon the carriage and normally in ineffective position and having connections to the ribbon withdrawing means, effective during the withdrawing of the ribbon from the printing field, to automatically move the deflector to an effective sheet-deflecting position close to the front of the platen, for guiding the leading edge of an inserted work-sheet across the typing line out of contact with the withdrawn ribbon, between the latter and the platen. 70

2. In a typewriting machine, the combination with a revoluble paper-feeding platen and a carriage-frame supporting said platen, a ribbon and means to withdraw the ribbon from the typing line of the platen, of paper deflecting means supported upon the carriage-frame and normally ineffective but shiftable by and with the ribbon-withdrawing means to deflect a work-sheet over the typing line and around the platen, between the platen and the withdrawn ribbon, to prevent the soiling of the work-sheet by contact with the withdrawing ribbon. 95

3. In a typewriting machine, the combination with a revoluble paper-feeding platen and a carriage-frame supporting said platen, a ribbon and mechanism to withdraw the ribbon from the typing line of the platen, of a shiftable paper-deflector pivotally supported upon the carriage-frame, and normally in ineffective position away from the platen but swingable by and with the ribbon-displacing mechanism to effective position close to the platen, to deflect a work-sheet, inserted at the rear of the platen over the typing line, to direct it between the platen and the withdrawn ribbon and prevent it from flaring away from the platen and into contact with said ribbon. 110

4. In a typewriting machine, the combination with a revoluble work-sheet-feeding platen and a carriage-frame supporting the platen, a ribbon and a ribbon-control operable to shift the ribbon to the typing line for typing and away from the typing line for work-sheet insertion, of a normally inoperative paper-guiding work-sheet deflector, substantially conforming to the platen-surface and pivotally mounted upon the carriage-frame, said deflector shiftable automatically 125

with and by said ribbon-control to vibrate said deflector to the typing line when the ribbon is shifted to be inoperative to type and vibrate the deflector away from the typing line when the ribbon is restored to cover the typing line after the insertion of the work-sheet for typing.

5. In a typewriting machine, the combination with a revoluble paper-feeding platen, 10 a carriage-frame supporting the platen, a ribbon for typing and mechanism to remove the ribbon from the typing line during the insertion of a work-sheet, of a paper-deflector, substantially conforming to the platen-surface and mounted upon a rail of the carriage-frame for a swinging movement to and from the platen in a substantially horizontal plane, said deflector normally away from the platen, and means to enable said deflector to 15 be shifted towards the typing line of the platen by the ribbon-removing mechanism, to guide the paper across the typing line, during the interval the ribbon is raised, and prevent fouling of the paper with the ribbon.

20 6. In a typewriting machine, the combination with a revoluble work-sheet-feeding platen, a carriage-frame supporting said platen, a ribbon and a ribbon-displacing mechanism to remove the ribbon from the 25 typing line of the platen, of a swingable paper-deflector supported upon the front rail of the platen-frame, and having a paper-deflecting blade, spring-means to hold the blade normally against the rail, and cam-means 30 operated by the ribbon-shifting mechanism, effective to engage and advance the blade towards the typing line, after the displacement of the ribbon from the typing line, and deflect the paper rearwardly over the platen 35 and under the ribbon.

40 7. In a typewriting machine, the combination with a revoluble platen and a carriage-frame supporting the platen, a ribbon and a ribbon-displacing mechanism effective to 45 raise and hold the ribbon above the typing line of the platen, of a swingable paper-deflecting means, including a lever fulcrumed upon the front rail of the platen-frame, said lever at one end formed with a paper-deflecting member, substantially conforming to the platen-surface, and normally positioned away from the platen, and means, carried by the ribbon-displacing mechanism, operative to 50 vibrate said lever, and advance the deflecting member towards the platen to deflect the advancing inserted paper over the typing line of the platen and under the ribbon to prevent fouling of the sheet against the displaced ribbon.

55 8. In a typewriting machine, the combination with a revoluble platen and a carriage-frame supporting the platen, a ribbon and a ribbon-displacing mechanism to raise the ribbon above the typing line of the 60 platen, of a swingable paper-deflecting

means, including a lever fulcrumed upon the front rail of the carriage-frame for a substantially horizontal movement towards and from the platen, said lever at one end formed with a paper-deflecting member, substantially conforming to the platen-surface, but normally positioned away from the platen, means carried by the ribbon-displacing mechanism and operative to cam said lever, to shift and hold the deflecting member in 70 paper-deflecting position adjacent the platen and while the ribbon is raised; and a spring operative to interruptively hold one end of said lever and the camming means in self-adjusting relation, so that the ribbon-mechanism and the deflecting member will adjust themselves to normal non-engaging positions.

9. In a typewriting machine, the combination with a revoluble platen and a carriage-frame supporting the platen, a ribbon and a ribbon-shifting mechanism operable to raise the ribbon above the typing line of the platen, of swingable paper-deflecting means, including a lever fulcrumed upon the front rail of the platen-frame for a substantially horizontal movement between the rail and platen, said lever at one end formed with a paper-deflecting blade-member, substantially conforming to the platen-surface, cam-means operable with the ribbon-shifting mechanism 95 for vibrating the other end of said lever to shift and hold the blade-member at the paper-deflecting position against the platen, and a spring on the rail operative to normally hold the blade-member under pressure 100 against the carriage-rail and afterward interruptively maintain coaction between lever and cam after the cam becomes effective, to provide an initial free movement of the ribbon-mechanism to remove the ribbon from 105 the typing line before the blade-member is vibrated to the platen.

10. In a typewriting machine having a revoluble paper-feeding platen mounted upon a carriage-frame, the combination with an auxiliary ribbon-mechanism mounted upon said carriage-frame and including a swingable ribbon-carrier presenting a horizontal line-length stretch of inking ribbon for duplicating purposes over the typing 115 line, said ribbon-carrier being manually operable to displace the horizontal ribbon-stretch clear of the platen during the insertion of a work-sheet around the platen up to the typing line, of a paper-deflector including a supporting horizontal lever and a vertical actuating arm all swingably mounted upon the carriage-frame, the deflector swingable to the platen by means on the ribbon-carrier engaging the vertical arm after displacing the ribbon, the deflector becoming effective to guide the same work-sheet across the typing line and under the displaced ribbon.

11. In a typewriting machine having a rev-

oluble paper-feeding platen mounted upon a substantially horizontal carriage-frame, the combination with an auxiliary ribbon-mechanism mounted upon said carriage-frame and including a movable ribbon-holder presenting a horizontal stretch of inking ribbon for duplicating purposes along the typing line from end to end of the carriage, said ribbon-holder operable to displace the horizontal ribbon-stretch clear of the platen, for inserting a work-sheet under the ribbon, of movable paper-guiding means including a lever fulcrumed upon the front part of the carriage-frame for movement in a horizontal plane, one end of said lever being formed with a paper-guiding blade, the other end operatively connected with said movable ribbon-holder in such a manner that displacing of the ribbon engages said blade at the platen-surface for guiding a work-sheet, during its insertion, upwardly across and beyond the typing line, while restoring of the ribbon causes said blade to recede to out-of-the-way inoperative position.

12. In a typewriting machine having a revoluble paper-feeding platen mounted upon a substantially horizontal carriage-frame, the combination with an auxiliary ribbon-mechanism mounted upon said carriage-frame and including a movable ribbon-holder presenting a horizontal stretch of inking ribbon for duplicating purposes along the typing line from end to end of the carriage, said ribbon-holder operable to displace the horizontal ribbon-stretch clear of the platen, for inserting a work-sheet under the ribbon, of movable paper-guiding means, said means including a lever fulcrumed upon the front part of the carriage-frame for movement in a horizontal plane, one end of said lever being formed with a paper-guiding blade, the other end provided with a cam-surface to co-operate with a cam-member on one end of said ribbon-holder in such a manner that displacing of the ribbon engages said blade against spring-pressure for guiding a work-sheet, during its insertion, upwardly across and beyond the typing line, while restoring of the ribbon causes said blade to recede to out-of-the-way inoperative position.

13. A typewriting machine having a carriage, a platen and a line-length manifold ribbon-mechanism on the carriage, said ribbon-mechanism manually displaceable to uncover the typing line of the platen preparatory to the insertion of a work-sheet to the typing line, and means on the carriage, normally separated from the platen and ineffective, for operating automatically during each ribbon-displacing movement to move towards the platen to deflect the work-sheet over the typing line and under the displaced ribbon.
